APPARATUS FOR SPRAYING BEAMED
YARNS

Helmut Voelker, Silvertown, Ga., and William H. Wolfe, Lancaster, S. C., assignors to The B. F. Goodrich Company, New York, N. Y., a corporation of New York

Application October 10, 1942, Serial No. 461,622

2 Claims. (Cl. 68—205)

1

This invention relates to the treatment of yarn with liquids and is particularly useful in the application of mildew inhibitors, dampening solutions, and the like.

In the manufacture of cord for tires, belts and other products it has been found desirable to treat the cord material in the yarn stage by applying liquids thereto. Difficulty heretofore has been encountered in obtaining uniform treatment without using excessive liquid such as to wet the surroundings and waste objectionably.

The present invention aims to overcome the foregoing and other difficulties.

The principal objects of the invention are to provide highly uniform wetting of the yarns by continuous treatment, to provide substantially complete saturation, and to provide for regulating the amount of treatment.

A further object is to provide for effectively treating the yarns upon the beams during the warping process.

These and other objects will appear from the following description and the accompanying drawings.

Of the drawings:

Fig. 1 is an elevation of apparatus illustrating and embodying the invention.

Fig. 2 is a cross-section thereof taken on line 2—2 of Fig. 1.

In accordance with the invention a row of spraying mechanisms are constructed in a manner to provide a uniform spray across the length of a beam, the spray being directed against the surface of a beam while yarns are being beamed thereon, and the spraying mechanism is maintained at a constant distance from the yarns during the beaming operation. Provision is made for obtaining a high degree of uniformity in the application of the spray to the yarn.

Referring to the drawings, the numeral 10 designates a warp beam supported rotatably in bearings 11, 12 of a suitable beaming device (not shown) adapted to rotate it. The yarns 13 are led to the beam in parallel relation over a guide roller 14. A trough 15 as long as the beam is suspended under the beam by straps 16, 17 passing over pulleys 18, 19 rotatably mounted in pedestals 20, 21. Weights 22, 23 are suspended from the other ends of the straps. The trough is guided for vertical movement by lugs 24, 25 slidably fitted in guides 26, 27 fixed to the floor 28 below the beam. A pipe 30 is mounted in the trough 15, lengthwise thereof, and a series of spray heads 31 are mounted on the pipe in spaced apart relation therealong and in com-

2

munication with the interior of the pipe. The spray heads are directed to spray fluid vertically against the beam. A flexible hose 32 supplies fluid under pressure from any desired source (not shown) to one end of the pipe, the other end being closed by a cap 33.

A shield 34 in the form of an inverted trough of rectangular cross-section and closed at its ends is supported from the trough 15, as by cross bars 35. A slot 36 in the top of the shield extends therealong parallel to the axis of the beam and over the spray heads and is adapted to limit the spread of the spray reaching the face of the beam, the width of the slot being preferably adjustable, as at 36a. The shield is shorter than the distance between flanges 10a, 10b of the beam so as to clear them and has brackets 37, 38 fixed thereto at its opposite sides in which free-running rollers 39, 40 are journaled in position to contact with the face of the beam or the yarns thereon. A flexible drain pipe 41 is provided to drain excess liquid from the trough 15. For best results it is desirable that the spray give a generous delivery within the shield, the surplus being recovered by means of the trough and drain.

The weights 22, 23 are made sufficiently heavy to overbalance the trough, spray pipe, and shield, so as to cause the rollers 39, 40 to contact with the surface of the beam or the yarn thereon at all times to maintain the spray heads at a substantially constant distance from the material on the beam. The arrangement is such that as the yarn is beamed a substantially uniform spray in the form of a band extending axially of the beam is projected against the yarn as it is beamed and the spray is applied constantly and uniformly throughout the beaming operation. Each yarn is given uniform treatment and each convolution of yarn is subjected to successive wettings at successive revolutions by contact with succeeding convolutions being sprayed. The slot 36 may be made adjustable by a slideable shutter 36a mounted on the shield.

In the operation of the apparatus, a beam 10 is rotatably mounted in its bearings above the sprays, and a plurality of yarns are led over the guide roller 14 and their ends are fixed to the beam. Liquid under pressure is supplied to the spray heads and during rotation of the beam the yarns are wound thereon and passed continuously through the spray where they are uniformly treated. In this action the liquid reaching the beam is controlled by the opening in the shield 34, and surplus liquid drops from the shield into the trough 15 for recovery.

Variations may be made without departing from the scope of the invention as it is defined by the following claims.

We claim:

1. Apparatus for treating yarn, said apparatus comprising a beam rotatable about a horizontal axis for simultaneously beaming a plurality of yarns, spray means for continuously applying a spray of liquid to the yarn as it is beamed, said spray means comprising a plurality of spray heads located below the beam directed at the lower face of said beam in closely spaced-apart relation to provide a substantially uniform upwardly directed spray across the face of the beam, an adjustable shield between said spray heads and said beam for restricting the spread of the spray, means below said shield and said spray heads for recovering the excess sprayed liquid, spacing means including rollers bearing against the lower face of the yarn on the beam, and means for urging and guiding said rollers, said shield, and said spray heads as a unit toward the face of the beam for maintaining said spray heads at constant distance from the yarn on the beam.

2. Apparatus for treating yarns, said apparatus comprising a rotatable beam for beaming yarn thereon, spray means extending along and below the face of the beam for applying a spray of

liquid to the yarn as it is beamed, said spray means comprising a row of spray heads, a slotted shield for confining the spray from said heads, means for adjusting the width of the slot in said shield, means for moving the said spray means toward and away from said beam, and means for maintaining the spray heads at a uniform distance from the yarn on said beam.
